UNITED STATES PATENT OFFICE.

ANDRÉ VIRGILE PAUL MARIE BERTHIER, OF CONSTANTINOPLE, TURKEY.

AUTOMATIC GUN.

No. 918,646.

Specification of Letters Patent.

Patented April 20, 1908.

Application filed June 2, 1905. Serial No. 288,456.

To all whom it may concern:

Be it known that I, ANDRÉ VIRGILE PAUL MARIE BERTHIER, a citizen of the Republic of France, and resident of Constantinople, Turkey, have invented certain new and useful Improvements in Automatic Guns, of which the following is a specification.

This invention relates to new and useful improvements in automatic guns and it has for its object the provision of a novel device of this character wherein the force necessary to the operation of the mechanisms of the gun is borrowed from the gases evolved at the moment of firing.

It is also an object of the invention to provide a gun wherein the several parts thereof will be simple in construction, economical to manufacture, and efficient in practice.

With the foregoing and other objects in view, the invention consists in the details of construction and in the arrangement and combination of parts to be hereinafter more fully set forth and claimed.

In describing the invention in detail reference will be had to the accompanying drawings forming a part of this specification wherein like characters denote corresponding parts in the several views, in which—

Figure 1, is a view, partly in elevation and partly in section of a fragment of a gun with the invention applied thereto. Fig. 2, is a longitudinal section of Fig. 1. Fig. 3, is a view of a stop employed in the invention. Fig. 4, is a plan view of the trigger mechanism. Figs. 5 and 6, are views in detail of the firing pin and its operating lever. Fig. 7, is a sectional view taken on the line 7—7 of Fig. 2. Fig. 8, is a fragmentary view in elevation of a gun with the invention applied thereto. Fig. 9, is a sectional view taken on the line 9—9 of Fig. 8. Fig. 10, is a detail view of the operating lever. Fig. 11, is a sectional detail view of the cylinder employed in the invention. Fig. 12, is a side elevation of the magazine employed in this invention. Fig. 13, is an end elevation thereof. Fig. 14, is a section taken on the line 14—14 of Fig. 1, illustrating the magazine in position. Figs. 15, 16, and 17, illustrate a modified form of the invention.

This gun comprises in its construction, what may be termed an automatic mechanism, a closing mechanism, a trigger mechanism and a magazine.

The "automatic mechanism" more particularly illustrated in Figs. 8, 9, and 11, con-

sists of a cylinder formed in two sections, section 1, being stationary and formed integral with the breech box, while the other section 2, is removable and has its rear end engaged in the first section and its front end screwed into the thickened portion 3, of the barrel, where the gas is taken out. The thickened portion 3, is integral with the barrel and is provided with a passage 4, intended to admit the gases. This thickened portion 3, receives, as before stated, the front end of the movable section 2, of the cylinder. In the outer end of the section 2, of the cylinder is arranged a screw 5, which screw controls the volume of the chamber within the section, and threaded through the thickened portion 3, is a screw valve 7, which controls the admission of the gases through the passage 4. Within the cylinder extends a piston rod 8, having the head 6, and tightening washer 9, and a spiral spring 10, surrounding the piston rod. The piston rod 8, in practice, is connected at its rear end in any suitable way to the cylinder-actuating lever, hereinafter described.

The "closing mechanism" comprises in its construction three parts; the bolt 11, the actuating lever 18, carried by the firing pin, and the extractor 17. The bolt 11, carries, at its front, two symmetric locking lugs 14, 15. In the body of the bolt is a groove 16, which begins at its front end and is parallel to the axis of the bolt a distance determined by the stroke of the firing pin at the moment of firing. At this point the rectilinear groove is changed into a helicoidal incline, the length of which corresponds to a certain rotation of the bolt, 70°, in the view illustrated. The helicoidal part of the groove then extends transversely a distance about its width. The bolt carries the extractor 17, which partakes of its motion. The extractor may be mounted upon a ring but does not rotate. The cylinder has at its lower part a groove *m*, the width of which is equal to the thickness of the heel *q*, of the ejector and another small groove *n*, the smaller width of which is equal to the thickness of the nose *b*, of the ejector. These two grooves are separated from each other in such a manner that the incline which terminates the groove *m*, causes the ejector *E*, to be tilted around its tenon *t*, and the nose *b*, to take behind the cartridge *C*, which is drawn backward in the cylinder. The cartridge thus stopped in its motion, oscillates around the claw of the extractor 17, and

is projected outside. When the cylinder comes back to close again, the nose *b*, is raised when it meets the incline terminating the groove *n*; the heel *q*, engages the groove 5 *m*, and in no way hinders the motion of the cylinder. The operating lever 18, and the firing pin 12, are integral and upon the firing pin is formed a tenon 19, which rides in the groove of the bolt as before described. Al- 10 though not shown, mention may be made of the fact that in lieu of one tenon, a plurality of the same may be employed.

When the firing pin has been thrown forward, the lever 18, is drawn back along the 15 gun either by exerting a tractional effect on the handle or by the action of the gases borrowed from those which are evolved at the moment of firing. It first accomplishes the rectilinear stroke corresponding to the dis- 20 tance necessary for insuring the percussion.

At this moment, the tenon 19, of the firing pin, which up to this time has moved in a rectilinear groove of the bolt, encounters the helicoidal part 16, of the groove. The firing 25 pin, which is kept by its lever engaged in a guide groove 20, of the receiver, is prevented from rotating, and continuing its backward motion it forces the bolt to rotate from the right to the left, until said locking lugs 30 14 and 15, are disengaged completely. The bolt may participate in the rectilinear motion of the lever, but it is not sufficiently connected with it. In order to obtain this result, the grooves 21, for the passage of the 35 lugs in the receiver, comprise at their front an inclined portion 22, the inclination of which is such that the bolt engaging it by means of its lugs continues its rotation to the left about 40°, when the latter rotation is 40 effected. The locking lugs are horizontal. The tenon 19, of the firing pin has then engaged the transverse part of the groove of the bolt and the connection of the two pieces is complete. The movement of the closing 45 mechanism is then reversed carrying with it the shell just discharged until the shell meets with the ejector which throws it out of the receiver. The upper cartridge of the magazine is raised and placed in advance of the 50 bolt. At this moment, the action of the borrowed gases is determined. They escape through the opening *a*, Fig. 8, of the cylinder 2, and the spring 10, acting against the rear face of the piston head 6, carries the closing 55 mechanism ahead. The reverse movements of those which have been explained before for the opening, are produced. The bolt rotates and closes itself again.

The "trigger mechanism" comprises a 60 sear 23, carrying at its rear, between the tail 24, and its pivot 25, an arm 26, into which is screwed one or more coils of the coiled spring 27, which is intended to act not only as a spring for the sear, but as a 65 trigger spring.

The gun being cocked, the action of the finger on the trigger 28, causes it to oscillate around the pivot. The heel 29 of the trigger which consists of a detent pivoted to the trigger 28 at 30, and having a spring 31, 70 which has a constant tendency to force said heel back, contacts with the tail of the sear and raises the same until the head 23, of the sear clears the passage and allows the cartridge to be fired. The heel of the trigger, 75 owing to its special form (Fig. 4) escapes and is carried in front of the tail 24 of the sear, which, under the action of its spring returns to its normal position. When the pull on the trigger is released, 80 the trigger is carried back to its original position by the spring of the sear. The heel of the trigger is closed and meets with the tail of the sear and when it has passed the tail it returns to its former position 85 under the tail.

The receiver may be kept opened at will by a stop 32, having the same shape as the head of the sear. The stop 32, is held normally in position for action by a coiled 90 spring 33, said stop having its head projecting into the receiver. When the automatic feature of the gun is to be employed, the stop 32, is lowered and kept in this position by a small shaft 33', arranged 95 transversely of the receiver and provided with a radial arm 35, which when turned down upon the stop depresses the same and holds it out of action.

The magazine 36, is made of one piece of 100 sheet metal preferably steel and is adapted to contain an odd number of cartridges 37, arranged as shown in Figs. 2 and 14. The magazine is placed into the gun from below. A tongue 38, is cut out from the rear part 105 of the magazine and has its free end curved outwardly in order to act as what might be termed a "push-member." This tongue is also slightly convexed toward the exterior in order to give it a spring action. 110

Struck out of the tongue 38, are two projections 39, and 40, which are intended to engage the receiver and to hold the magazine in position. When the upper projection 40, of the tongue engages the receiver, the first cartridge of the magazine cannot be engaged by the bolt and thereby provides a safety. Pressure exerted upon the magazine permits the engagement of the second tongue 39, and the gun is then 120 ready for use. Arranged at the top of the magazine on opposite sides thereof, are two cheeks 44, for guiding the cartridge which is about to be introduced into the receiver. The follower 41, made of bent steel sheet 125 acts as an elevator which is continuously pushed toward the top by the action of the spring 42. The follower is provided with a projection 43, obtained by stamping, which is placed beneath the lowermost cartridge 130

of the vertical row containing the smaller number of cartridges.

As may be readily seen from the foregoing description, the magazine may be refilled while it remains in place by means of charging blades introduced in the magazine, thus any loss of time may be avoided for the refilling operation.

In Figs. 15 and 16, a modified form of the invention is illustrated. In order to diminish the volume of the gun, the cylinder which receives the borrowed gas, instead of being arranged on the side of the barrel is arranged under it. To this end, in order to avoid hindrance by the magazine, the cylinder has been somewhat advanced, making it, if necessary, a little shorter. The spring is then arranged in a corresponding manner.

The arrangement of the gas inlet and the construction of the piston head and the other features of the invention are the same as those described with reference to the first or preferred form. On the rear part of the piston rod is mounted, at right angles, an arm 45, connected to a flat rod 46, the section of which may be seen in Fig. 16. This figure shows a transverse section of the device taken at the place where the barrel is thicker, while Fig. 15, is a view taken from below the gun without a stop.

Fig. 17, is a section similar to that of Fig. 9. The rod 46, is guided in the way 47, bearing a corresponding shape and arranged in the receiver in such a manner that the projection thus formed on the side of the gun is very small. It is furthermore completely hidden by the barrel of the gun and finally the blade 46, may be connected in any convenient manner to the actuating lever of the firing pin as before stated. The function of

a gun provided with this particular arrangement of the gas cylinder is exactly as that hereinbefore described.

Having fully described my invention what I claim as new and desire to secure by Letters Patent, is—

1. A gun of the class described comprising a cylinder arranged to communicate with the barrel-chamber and containing a spring-pressed piston adapted to be actuated by the gases of the explosion in one direction, a receiver, a bolt arranged in said receiver adapted to be operated by said piston and equipped with locking lugs and having a groove therein parallel with the bolt axis for a certain portion thereof, said groove being of a helicoidal outline for the rest of its area, and a firing pin having connection with said bolt by means of said groove, and a member thereon engaging said groove, said bolt locking lugs having sliding engagement with said receiver.

2. A gun of the class described comprising a cylinder arranged to communicate with the barrel-chamber and containing a resiliently held piston adapted to be actuated by the gases of the explosion in one direction, a receiver, a bolt adapted to be operated by said piston having locking lugs engaging grooves in said receiver, said bolt also having a groove therein parallel with the bolt axis for a portion of its area and helicoidal in outline for its remaining area, and a firing pin having a lug and connection with said bolt by means of said lug engaging the said groove.

In testimony whereof I have hereunto set my hand in presence of two witnesses.

ANDRÉ VIRGILE PAUL MARIE BERTHIER.
